UNITED STATES PATENT OFFICE.

GERALD B. STOUT, OF DENVER, COLORADO.

FENCEPOST.

1,335,302.

Specification of Letters Patent. Patented Mar. 30, 1920.

Application filed March 6, 1918. Serial No. 220,869.

To all whom it may concern:

Be it known that I, GERALD B. STOUT, a citizen of the United States, residing in the city and county of Denver and State of Colorado, have invented certain new and useful Improvements in Fenceposts; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in posts adapted for use where the fence is subjected to the action of floods which ordinarily destroy the fence and carry it away. My improvement is of such character that 20 when employed in constructing a fence across a stream, as a normally dry creek, the portion of the fence above the bed of the creek may by reason of breakable pins employed in the construction of the posts, 25 yield to the action of the flood and lie flat upon the bed of the stream without destroying anything except the breakable pins with which the two hinged parts of the posts are connected beyond the hinge pin in 30 such a manner that they yield to the force of the flood before any part of the fence is destroyed. The wires which ordinarily would be employed in the construction of a fence of this character are, of course, applied to the upper hinged members of the 35 post and extend above the bed of the creek or draw where the fence is located.

Having briefly outlined my improvement, I will proceed to describe the same in detail, reference being made to the accompanying drawing, in which is illustrated an embodiment thereof. In this drawing:

Figure 1 is a perspective view of my improved fence post.

45 Fig. 2 is a fragmentary view of the structure showing the several parts detached, but in position for assemblage.

Fig. 3 is a fragmentary side of the post, showing also an end view of the two projecting parts which are normally connected with the breakable pin.

Fig. 4 is an elevation of the fence.

Fig. 5 is a top plan view showing the part of the fence above the bed of the stream in 55 the flat position after the force of the flood has broken the wood pins of the posts.

The same reference characters indicate the same parts in all the views.

Let the numeral 5 designate my improved post, considered in its entirety and composed of an upper member 6 having a right-angled projection 7 and a lower member 8 having a right-angled projection 9, the two projections 7 and 9 being normally arranged in abutting relation, the member 7 having a groove 10 in which is located a tongue 12 of counterpart shape, the two members having registering perforations 13 and 14 through which is passed a breakable pin 15, the pin being located near the outer or free extremities of the members 7 and 9, the two parts of the post being hinged, as shown at 16, a bolt 17 constituting the hinge pin and passing through registering perforations 18 and 19 formed in the respective posts parts. 75 It is feasible to have the arm 7 sufficiently heavy to maintain member 6 normally in upright position without using a breakable pin.

It is assumed that the post is made of 80 metal and that the breakable pin 15 is made of wood and sufficiently frail to yield or break under a force that would otherwise injure or destroy the post or the fence with which it is employed. It must be understood, however, that the post may be made of any suitable material. For instance, the two parts 6 and 8 may be of hard wood and the pin 15 of soft wood and sufficiently frail to be breakable under the aforesaid conditions. 85

The use of the posts is illustrated in Figs. 4 and 5. The member 8 of each post is inserted in the bed until its projection 9 is in contact with the surface or approximately so, the part 8 being made long enough to properly anchor the post, considering the conditions of the ground where it is inserted. Of course, if this material is sand and very loose at the surface it will 95 be necessary to have the part 8 sufficiently long to reach a solid or secure stratum of material. Hence the length of this member will be regulated according to the conditions of the earth where the device is employed. 105

From the foregoing description, the use and operation of my improved post will be readily understood. In Figs. 4 and 5 a number of these posts is illustrated, the members 8 being anchored in the bed 20 of a dry creek or draw, while wires 21 are ap- 110

plied to the upper members 6 of the posts on the side toward which the flood will approach. Normally, the breakable pins 15 are in place and intact. Now, when a flood 5 strikes the fence moving in the direction indicated by the arrows in Fig. 5, the pressure on the fence section will be sufficient to break the pins 15 of all the posts, in which event the members 6 of all the posts, 10 together with the wires attached, will swing downwardly on the hinge pins 17 and assume a flat position on the bed of the stream, as shown in Fig. 5. After the 15 flood is past and the bed of the stream is in proper condition, the panel of fence may be raised and new breakable pins 15 inserted, after which the structure is ready for use, the expense of restoring it to its normal condition being inconsiderable or 20 negligible, as will be readily understood.

Having thus described my invention, what I claim is:

1. A post comprising upper and lower members hingedly connected, the hinge be-

ing substantially within the body of the 25 post when the two members are in alinement, each member having at its hinged end a laterally projecting arm, the arm on the lower member being adapted to support the 30 arm on the upper member, one of said arms having a recess and the other a projection to engage in said recess whereby said arms may be properly positioned.

2. A post comprising upper and lower members hingedly connected, the hinge being 35 substantially within the body of the post when the two members are in alinement, each member having at its hinged end a laterally projecting arm, the arm on the lower member being adapted to support the 40 arm on the upper member, one of said arms having a recess and the other a projection to engage in said recess, whereby said arms may be properly positioned, said tongue and the walls of said recess having apertures 45 adapted to aline to receive a breakable pin.

In testimony whereof I affix my signature.
GERALD B. STOUT.
